UNITED STATES PATENT OFFICE.

HARRY P. KING, OF MARSHALL, MISSOURI.

SUPPORTING DEVICE.

Application filed March 17, 1925. Serial No. 16,156.

To all whom it may concern:

Be it known that I, HARRY P. KING, a citizen of the United States, residing at Marshall, in the county of Saline and State of Missouri, have invented certain new and useful Improvements in Supporting Devices, of which the following is a specification.

This invention relates to improvements in supporting devices, and is more particularly adapted to a device which is to be used for supporting a tray.

One of the important objects of the present invention is to provide a supporting device which may be used for various purposes such as supporting a pan used for various kitchen purposes, the device further being adapted to support a draining bag which is used particularly in pickling or preserving.

A further object of the invention is to provide a supporting device of the above mentioned character, which includes an upright, and a laterally disposed supporting arm, means being provided for enabling the arm to be readily and easily adjusted in any vertical position on the upright, additional means being provided for permitting the swinging movement of the arm on the upright.

A further object is to provide a supporting device of the above mentioned character wherein the same is of such construction as to enable the several parts to be readily assembled or disassembled, means being associated with the upright for permitting the securing of the same on any suitable support such as a table or chair in a detachable manner.

A further object is to provide a supporting device of the above mentioned character which is simple in construction, inexpensive, strong and durable and further well adapted for the purpose for which it is designed.

Other objects and advantages of this invention will become apparent during the course of the following description.

In the accompanying drawing forming a part of this specification and in which like numerals designate like parts throughout the same:

Figure 1 is a side elevation of the supporting device embodying my invention showing the manner in which a pan is supported on the laterally extending arm.

Figure 2 is a similar view showing the device used in supporting a draining bag.

Figure 3 is an enlarged detail of the inner end of the laterally extending arm and a portion of the threaded upper portion of the upright, and

Figure 4 is a fragmentary detail of the pan or tray illustrating the channel associated therewith for receiving the arm.

In the drawing, wherein for the purpose of illustration is shown the preferred embodiment of my invention, the numeral 1 designates an upright, the same being in the form of an elongated rod, the upper portion of which is threaded as illustrated at 2. A bracket designated generally by the numeral 3 is associated with the lower end of the upright and the same includes laterally extending spaced members 4 and 5 respectively. A screw clamp 6 of any conventional construction is associated with the laterally extending member 4 and cooperates with the member 5 in securing the upright 1 in a detachable manner on any suitable support such as a chair seat or table top in the manner as clearly illustrated in the drawing.

The supporting device furthermore includes an elongated supporting arm 7, the same being preferably rectangular in cross section. A transversely extending sleeve 8 is provided at the inner end of the elongated supporting arm 7. This sleeve is of a suitable length, and the same is cut away at its respective ends to provide a pair of opposed substantially semi-circular portions 9 and 10. The sleeve is internally threaded at its ends, and the purpose thereof will herein-after be more fully described.

In securing the arm 7 in position on the upright 1, the arm has its sleeve 8 disposed over the threaded upper portion 2 of the upright and it is obvious that when the arm is disposed at a slightly upward incline with respect to the upright, the same may be moved vertically on the upright in a simple and efficient manner, and without causing the threads of the uprights coming in contact with the threads on the inner faces of the semi-circular portions 9 and 10 respectively.

When the supporting arm 7 is disposed in a substantially horizontal position, the opposed semi-circular portions 9 and 10 of the sleeve 8 will engage the threaded portion of the upright and support the arm in a horizontal position. Furthermore, the threads on the inner faces of the semi-circular portions 9 and 10 will cooperate with the

2
threaded portion 2 of the upright in permitting the arm 7 to swing with respect to the upright. The construction of the sleeve in the manner as above set forth permits the 5 supporting arm to be readily and easily adjusted to any vertical position on the upright as may be desired.

When the supporting arm 7 is adapted to support a tray or pan, the latter which is 10 designated by the numeral 11 is provided on its bottom at the central portion thereof with the substantially rectangular channel 12 so as to enable the outer end of the rectangular arm 7 to be received therein and 15 prevent any tilting movement of the pan or receptacle on the supporting arm, thereby enabling the latter to be detachably supported on the arm. The pan or tray 11 may be used for various purposes such as holding 20 kitchen utensils or various edibles which are to be prepared. The tray or pan may not only be used for kitchen purposes, but may also be used for numerous other purposes.

In Figure 2 of the drawing, I have illustrated 25 the device as being used for supporting the bag 13, the same being particularly used in pickling or preserving. The supporting arm 7 is arranged on the threaded upper portion 2 of the upright 1 at such a 30 height as to permit the bag 13 to be drained. It is of course understood that a suitable receptacle is placed underneath the bag to catch the drippings.

It will thus be seen from the foregoing 35 description, that a supporting device has been provided which may be readily and easily set up in position for use, and further

adjusted so as to enable the user of the device to have ready access to the pan or tray supported on the arm which extends laterally 40 from the upright. Furthermore, the arm and pan may be swung toward or away from the person.

While I have shown the preferred embodiment of my invention, it is to be understood that various changes in the size, shape and arrangement of parts may be resorted to without departing from the spirit or scope 45 of the appended claim.

Having thus described the invention, what 50 I claim as new is:

A supporting device of the class described comprising an upright, the upper portion thereof being threaded, a bracket associated with the lower end of the upright, means for 55 securing the bracket to a suitable support, a laterally extending article supporting arm, a sleeve carried by the inner end of said arm and disposed transversely of the arm, said sleeve being cut away at its respective ends 60 to provide a pair of opposed semi-circular portions whereby the inner end of the arm may be readily adjusted in any vertical position on the upright, when the arm is disposed upwardly at an incline so that the 65 semi-circular portions of the sleeve are out of engagement with the uprights, the semi-circular portions of the sleeve being internally threaded for cooperation with the threaded upright to permit the swinging 70 movement of the laterally extending arm with respect to the upright.

In testimony whereof I affix my signature.
HARRY P. KING.
